UNITED STATES PATENT OFFICE.

LORENA B. NICHOLAS, OF LOS ANGELES, AND FRANK H. HEINE, OF SANTA ANA,
CALIFORNIA.

TOY AEROPLANE.

Application filed November 22, 1919. Serial No. 339,981.

To all whom it may concern:

Be it known that we, LORENA B. NICHOLAS and FRANK H. HEINE, citizens of the United States, residing at Los Angeles and at Santa Ana, respectively, in the county of Los Angeles and of Orange, respectively, and State of California, have invented new and useful Improvements in Toy Aeroplanes, of which the following is a specification.

10 Our object is to make a toy aeroplane, and our invention consists of the novel features herein shown, described and claimed.

Figure 1 is a top plan view of a toy aeroplane embodying the principles of our invention, the view being taken looking in the direction indicated by the arrows 1 in Figs. 2 and 3.

Fig. 2 is a side elevation looking in the direction indicated by the arrows 2 in Figs. 1 and 3.

Fig. 3 is a front elevation as seen looking in the direction indicated by the arrows 3 in Figs. 1 and 2.

Fig. 4 is a view in elevation illustrating the use and operation.

The body 1 is made from a solid stick of wood and comprises a head 2, a nose 3, and a tail 4. The head 2 is rectangular in cross section and has a flat upper face 5, and a flat lower face 6. The nose 3 extends from the head 2 and is round in all directions. The tail 4 extends backwardly from the head 2 a considerable distance and is tapered from the head backwardly. The upper lifting

30 plane 7 is a flat, thin, rectangular board fitting against the flat face 5 of the head 2 and secured in place by nails 8 driven downwardly through the board into the head.

The lower lifting plane 9 is a similar flat, thin, rectangular board fitting upwardly against the flat face 6 and secured in place by nails 10 driven upwardly through the board into the head. Preferably the lower

40 lifting plane 9 is somewhat smaller in plan than the upper lifting plane 7. The forward edges 11 and 12 of the lifting planes 7 and

9 are bevelled so as to cut the air easily, and the outer ends 13 and 14 of the lifting plane 7 are bevelled from the lower face, and

45 in a like manner the outer ends 15 and 16 of the lifting plane 9 are bevelled from the lower face.

A propeller 17 fits against the point of the nose 3, and a nail 18 is inserted loosely

50 through a bore at the axial center of the propeller and driven into the material of the nose 3.

A vertical tail fin 19 is inserted into a slot 20 sawed vertically from the rear end of the tail and glued in place. The side fins 21 and 22 are formed integral from a single piece of board, and the board is fitted upwardly against the lower face of the tail 4, and nailed and glued in place, so that the side fins 21 and 22 are at right angles to the vertical fin 19. The side tail fins 21 and 22 are slightly inclined from rear to front relative to the level of the lifting planes 7 and 9. The extreme rear ends of the side tails being substantially on a level with the lifting plane 7, and the forward ends of the fins being on a line between the rear ends and the front edge of the lifting plane 9.

A strong cord 23 is secured at one end to a staple 24 driven downwardly into the forward end of the head 2, and a similar cord 25 is secured at one end to a staple 26 driven downwardly into the central portion of the tail 4. The upper ends of the cords 23 and 25 are secured together, or the cords may be

60 formed integral, and a third cord 27 is secured to the upper ends of the cords 23 and 25 and has a handle 28 upon its free end. In

65 attaching the cords 23 and 25 and the cord 27 care should be taken to get the cord 27 attached to the cords 23 and 25 so as to be at the center of gravity, so that when the operator holds the cord 27, or the handle 28,

70 as in Fig. 4, the aeroplane will remain in a horizontal position.

A strong cord 23 is secured at one end to a staple 24 driven downwardly into the forward end of the head 2, and a similar cord 25 is secured at one end to a staple 26 driven downwardly into the central portion of the tail 4. The upper ends of the cords 23 and 25 are secured together, or the cords may be

75 formed integral, and a third cord 27 is secured to the upper ends of the cords 23 and 25 and has a handle 28 upon its free end. In

80 attaching the cords 23 and 25 and the cord 27 care should be taken to get the cord 27 attached to the cords 23 and 25 so as to be at the center of gravity, so that when the operator holds the cord 27, or the handle 28,

85 as in Fig. 4, the aeroplane will remain in a horizontal position.

If the operator grasps the cord 27, or the handle 28 firmly and whirls the aeroplane as a sling is whirled, the propeller 17 will run at a high rate of speed and make a humming noise and more or less rattle, and the aeroplane will sail round and round within the

90 limits of the cord and the swing of the hand.

Various changes may be made without departing from the spirit of our invention as claimed.

We claim:

A toy aeroplane comprising a fish shaped body member formed of a solid piece of wood and having a nose and a tail, a propeller blade rotatably mounted on a pin on the nose of the body member, a double bladed tail for the body member, one blade being set horizontally and a second blade being set at right angles to the first, a lifting plane mounted across the top of the body

member, adjacent to the nose, a second lifting plane mounted across the bottom of the body member adjacent to the nose forming a biplane construction for the toy, a cord fastened to the top of the body member adjacent to the propeller, another cord fastened to the top of the body member at a point intermediate the wings and the tail, a third cord at-

tached to the outer ends of the two cords just mentioned, and a handle at the outer end 10 of the third cord for swinging the toy horizontally.

In testimony whereof we have signed our names to this specification.

LORENA B. NICHOLAS.
FRANK H. HEINE.
